UNITED STATES PATENT OFFICE.

JOSEPH F. BENOIT, OF SANFORD, MAINE, ASSIGNOR TO SANFORD MILLS, OF SANFORD, MAINE, A CORPORATION OF MAINE.

LOOM.

Application filed January 25, 1923. Serial No. 614,907.

To all whom it may concern:

Be it known that I, JOSEPH F. BENOIT, a citizen of the United States, and resident of Sanford, county of York, State of Maine, have invented an Improvement in Looms, of which the following description, in connection with the accompanying drawing, is a specification, like characters on the drawing representing like parts.

10 This invention relates to looms and has for its object to provide an improved loom with a novel and simplified mechanism for vibrating the lay and operating the picker sticks.

15 In accordance with my invention the movement of the lay is secured through the medium of a cam mounted on a cam shaft instead of by means of a crank shaft as is the usual custom and the cam mechanism is 20 arranged so that it not only operates to vibrate the lay but also affects the operative movement of the picker sticks.

The means for operating the lay is also constructed so that the lay has a cushioned 25 movement as the reed engages the fell of the cloth, thereby beating up the weft without subjecting the warp threads to undue strain.

In order to give an understanding of the 30 invention I have illustrated in the drawings a selected embodiment thereof which will now be described after which the novel features will be pointed out in the appended claims.

35 Fig. 1 is a side view of a loom embodying my invention;

Fig. 2 is an enlarged fragmentary sectional view showing the mechanism for operating the lay and the picker stick;

40 Fig. 3 is a view of the end of the lay showing the picker stick actuating mechanism.

Fig. 4 is a section on the line 4—4, Fig. 2.

I have shown at 1 a loom frame which 45 may have any suitable or usual construction, and at 2 I have illustrated the lay which is carried by the usual lay swords 3 that are mounted on the rock shaft 4. The lay 2 has the usual shuttle box 5 at each end and 50 each end of the rock shaft 4 has mounted thereon the usual picker stick 6 by which the shuttle is thrown across the lay.

55 My present invention relates to an improved means for operating the lay and the picker stick. The lay is given its vibrating

movement by means of cams carried by a cam shaft 7 and these cams are also provided with means for giving the picker stick 6 its operative movement.

Mounted on the cam shaft 7 are two cams 60 8, one at each end thereof, said cams engaging rolls 9 carried by arms 10 that extend rearwardly from the lay structure. The cams 8 are each provided with a high portion 11 and a low portion 12 and the 65 relative position of the roll 9 and the cam is such that when the roll 9 is in engagement with the low portion 12 of the cam as shown in full lines Fig. 2 the lay will be in its rearward position while when the cam 70 has turned so as to bring the high portion of the cam underneath the roll the arm 10 will be raised thereby moving the lay forwardly into the dotted line position and giving said lay its forward beat. The cam 8 75 will preferably be a double cam having two high portions 11 and two low portions 12 so that the lay will be given two forward beats for each rotation of the cam shaft.

This cam 8 also operates to retract the 80 lay from its forward to its rearward position and for this purpose I provide a swinging arm 13 which is pivoted to the loom frame at 14 and is provided with a roll 15 at its end bearing against the cam 8, said 85 arm 13 being connected to the lay structure by means of a spring 16. The relative positions of the rolls 9 and 15 is such that when one roll is on the low portion of the cam the other roll is on the high portion of the cam 90 and vice versa.

When the cam 8 makes a quarter turn from the position shown in Fig. 2 thereby to bring a high portion 11 underneath the roll 9 and cause the lay to beat forwardly, 95 a low portion 12 of the cam is brought into engagement with the roll 15 so that the arm 13 may swing forwardly. During the next quarter revolution when the roll 9 is passing from a high portion 11 of the cam to a low portion 12 the roll 15 will be engaged by a high portion of the cam and the backward movement of the arm 13 will act through the spring 16 to give the lay its backward movement.

As stated above I will preferably employ 100 two cams, one at each end of the lay, said cams thus operating to give the lay both its forward movement and its rearward movement.

I may, if desired, provide a yielding connection between the arm 10 and the lay structure, so that said arm can yield slightly when the roll 9 is passing over the portion 5 of the cam thereby producing a cushioned forward movement in the lay.

The arm 10 is pivoted to the lay at 17 and is provided with a stop portion 18 which rests on an extension 19 extending 10 rearwardly from the lay, said arm being held with the stop against the extension by means of a spring 20 which encircles a bolt 21 that extends upwardly through the extension and stop 18. The spring 20 is relatively stiff so that ordinarily it will not yield but it does provide a slight yielding movement between the arm 10 and the lay structure sufficient to give the lay a cushioned forward movement as the roll 9 is 20 passing over a high point 11 of the cam.

The cam 8 is also employed to give operative movement to the picker stick. Each picker stick is provided with a lug strap 22 which is connected to a strap or other flexible connection 23 that extends over a guide pulley 24 journalled on the loom frame and is connected to the end of an actuating lever 25 which extends rearwardly and is pivoted to the loom frame at 26.

30 Each cam 8 is provided with a picking roll 27 which is adapted to engage a roll 28 on the corresponding lever 25 thereby to depress the lever as shown in Fig. 2 and give the picker stick 6 its forward movement 35 through the flexible connection 23. Each cam 8 has a roll 27 thereon and, therefore, the corresponding picker stick is actuated once during each rotation of the cam shaft 7. The picking rolls on the two cams 8 at opposite ends of the shaft are oppositely situated so that during one half rotation of the shaft the picking roll at one end will actuate its picker stick and during the other half rotation of said shaft the picking roll 40 at the other end will actuate its picker stick. Hence at each rotation of the shaft 7 the lay will make two beats and each picker stick will be actuated once. This relative position of the two picking rolls 27 is shown in 45 Fig. 1 wherein the picking roll on the end of the shaft nearest the observer is shown at the rear of the cam and the other picking roll on the end of the shaft furthest from the observer is shown at the front.

50 The picking rolls 27 are preferably adjustably carried by the cam 8 so that the position thereof may be adjusted to properly time the action of the picker stick. Each picking roll is shown as mounted on a stud 29 which is carried in a slot 30 formed in the cam member 8, said stud being held in adjusted position by means of a clamping nut 31. With this arrangement the position 55 of the picking roll can be adjusted angularly of the cam so as to bring the action of

the picker stick into proper timed relation with the other elements of the loom.

An advantage resulting from using the cam 8 for operating the lay is that the cam may be shaped so as to give the lay a more 70 even reciprocating movement than results from the use of the rank shaft.

The cam shaft may be driven in any suitable way. In the construction shown it is driven from a driving shaft 32 which extends from the front to the rear of the loom and is journalled in suitable bearings 33 carried by the loom frame. This shaft has the belt pulley 34 thereon by which it is operated and it is geared to the shaft 7 by 80 means of suitable spiral gears 35.

I claim:

1. In a loom, the combination with a vibrating lay, of a picker stick, a cam shaft and a cam thereon operating both to vibrate 85 the lay and actuate the picker stick.

2. In a loom, the combination with a vibrating lay, of a picker stick, a cam shaft and a cam thereon operating at each revolution to give the lay two beats and the picker 90 stick one shuttle-throwing movement.

3. In a loom, the combination with a lay structure comprising pivoted lay swords and a lay carried thereby, of an arm pivoted to the lay structure and extending rearwardly therefrom, said arm having a stop projection, an extension rigid with the lay and with which the stop projection co-operates to limit the swinging movement of the arm in one direction, a spring yieldingly holding the stop in engagement with the projection, a cam shaft, a cam thereon acting on said arm and operating to give the lay its forward beat, and cam-actuated means yieldingly connected to the lay structure to give the latter its rearward movement. 100

4. In a loom, the combination with a vibrating lay, of a picker stick, an actuating lever connected to said picker stick, a cam 110 for vibrating the lay and a picking roll carried by the cam and giving said actuating lever its operative movement.

5. In a loom, the combination with a vibrating lay, of a picker stick, an actuating lever connected to said picker stick, a cam 115 for vibrating the lay and a picking roll adjustably carried by the cam.

6. In a loom, the combination with a vibrating lay, of a picker stick, a cam shaft, 120 a cam thereon for actuating the lay, a lever pivoted to the loom in the rear of the cam shaft, a flexible connection between the front end of said lever and the picker stick, and a picking roll carried by said cam and 125 actuating said lever.

In testimony whereof, I have signed my name to this specification.

JOSEPH F. BENOIT.
